ATTORNEY.

UNITED STATES PATENT OFFICE.

HARRY I. MACKEEVER, OF SAN FRANCISCO, CALIFORNIA.

DEVICE FOR COMPRESSING SPRINGS.

1,246,969.

Specification of Letters Patent. Patented Nov. 20, 1917.

Application filed November 27, 1916. Serial No. 133,599.

To all whom it may concern:

Be it known that I, HARRY I. MACKEEVER, a citizen of the United States, and a resident of the city and county of San Francisco, 5 State of California, have made a new and useful invention—to wit, Device for Compressing Springs; and I do hereby declare the following to be a full, clear, concise, and exact description thereof.

10 The invention is a device for compressing springs and is particularly designed for conveniently compressing and placing the springs around the stems of gas engine valves, to mount the valves, and for compressing said springs to remove the spring abutments on the stems in order to remove the valves.

15 In this specification and the annexed drawing I illustrate the invention in the form which I consider the best, but it is to be understood that I do not limit myself to such form because the said invention may be embodied in other forms, and it is also to be understood that I intend to cover the invention in whatever form it may be embodied within the scope and spirit of the claims following the description herein.

20 Referring to the drawing:

25 Figure 1 is a side view of the device shown in the act of compressing a gas engine valve spring on the valve stem.

30 Fig. 2 is an enlarged side view of the device.

35 Fig. 3 is a front elevation thereof.

40 Fig. 4 is a view of the device showing it in the act of compressing and placing a gas engine valve in position around the valve spring.

45 Fig. 5 is a detail view of the end of the lower arm of the device.

The device is formed with a U-shaped frame 1 having two arms 2 and 3 and their connecting member 4. The arm 2 has a fork 5 at its extremity adapted to surround a rod such as the stem of a gas engine valve. A bearing 6 is provided at the extremity of the arm 3 in which is slidably mounted a plunger 7, one end of which extends below the arm 3 in alinement with the center of the fork 5. An operating lever 8 is pivoted at 9 to the upper end of the bearing 6 at the side of the axis of the plunger toward the frame members 4, to which lever the upper end of a link 10 is pivoted at 11.

50 The plunger 7 is provided with a series of holes 12 which register with a slot 13 in said

bearing and are adapted to receive a pin 14 which is inserted through a hole 15 in the lower end of said link 10, whereby the lower end of the link may be adjustably connected 60 to said plunger. By placing the pin 14 in different plunger holes 12 the length of that part of the plunger projecting below the arm 3 may be varied as conditions require. On the upper face of the arm 2 rests 65 a bracket 16 having side flanges 17 which engage the side faces of said arm and hold the bracket in sliding alinement with the arm. A presser foot 18 is provided on the outer end of said bracket which is adapted 70 to engage the lower end of a spring or the spring abutment at said end of the spring. A screw 19 having a butterfly head 20, extends through a slot 21 in the upper wall of the bracket 16 and screws into the arm 75 2 so that said head engages said upper wall of the bracket, whereby the bracket is adjustably secured to said arm. Upon loosening said screw the bracket may be moved along the arm 2 and the presser foot 18 adjusted to the proper position with relation to the crotch of the fork 5, so that upon securing the bracket in such position by the screw, said presser foot may engage the spring abutment collar on the valve stem 80 85 and hold the crotch of the fork slightly away from the valve stem.

In order to explain the operation of the invention as clearly as possible that part of a gas engine including the valve mechanism 90 is illustrated in Figs. 1 and 4, in which figures 30 indicates the valve casing of the engine; 31 a valve; 32 the valve stem; 33 the valve spring surrounding the stem; 34 the spring abutment collar on the stem abutting 95 the lower end of the spring; 35 the pin extending through the stem for holding the abutment collar in position on the rod against the spring; 36 the cam plunger for engaging the lower end of the valve stem to 100 actuate the valve; and 37 the bearing on the engine in which the cam plunger operates.

The operation of the invention is as follows:

When it is desired to remove the valve 105 from its operative position on the engine, the cap inclosing the opening in the valve casing above the valve is first removed; the device is then placed in the position shown in Fig. 1 with the plunger 7 raised by lever 110 8 and projecting through said valve casing opening and engaging the top of the valve

31 in the center thereof, and with the fork 5 surrounding the lower end of the valve stem 32 and engaging the under side of said abutment collar, and the presser foot 18 engaging the edge of said collar and holding the crotch of the fork slightly away from the valve stem so that said crotch will not rub against the stem and create friction. The lever 8 is then swung down, during which operation the distance between the lever pivot 9 and the link and plunger pivot 14 increases, which causes the plunger 7 to press upon the valve 31 and lifts the frame 1, whereupon the fork 5 lifts the abutment collar 34 above the pin 35 and compresses the spring 33. When the lever has swung down to its lowermost position, the pivot 11 connecting the link and lever has swung forward to the side of the axis of the plunger 7 opposite to the side at which the lever 8 is pivoted, thus locking the plunger in its lowermost position and the device in its spring compressing position with the abutment collar above the pin 35. The pin is then driven out of the valve stem. The lever 8 is then lifted which allows the frame 1 to descend and the spring 33 to expand. The device is then removed and the valve is removed through the opening in the top of the valve casing.

Considerable difficulty has been experienced in placing the valve spring in position owing to the fact that when expanded its length is greater than the distance between the valve casing and the cam plunger bearing 37. The upper end of the spring must be placed against the lower wall of the valve casing to permit the valve stem to be inserted therein in which position the lower end of the spring bends outward and extends past the top of the cam plunger bearing 37. It is very difficult to compress the spring and bend it straight by hand so as to put the abutment collar in position on the valve stem. The difficulty is overcome by my invention as follows: The upper end of the spring 33 is first placed against the lower wall of the valve casing; the valve stem 32 and valve 31 are then introduced through the opening in the top of the valve casing and the valve stem inserted into the spring; the plunger 7 is then introduced through the opening in the top of the valve casing against the valve 31 with the lever 8 in raised position; the abutment collar 34 is placed against the lower end of the spring; the fork 5 is brought under said collar and the presser foot 18 against the edge thereof; the lever 8 is then swung downward causing the frame 1 to move upward and the fork 5 to compress the spring until the lower end of the spring, the collar 34 and the fork 5 rest above the top of the cam plunger bearing 37; the lower part of the frame 1 is then pressed inwardly against the tension of the

curvature of the lower end of the spring until the hole in the collar 34 registers with the lower end of the valve stem; the lever 8 is swung down to its lowermost position, during which movement the frame moves farther upward and the fork 5 pushes the collar on the valve stem and compresses the spring 33 until the collar is above the pin hole in the valve stem, in which position the device and the collar and spring are locked by the lever and link, their connecting point 11 being to the left of the plunger axis; the pin 35 is then driven through the hole in the valve stem and the lever 8 raised to let the collar, under pressure of the spring, down upon the pin. The valve is then properly mounted and the device is removed.

Having thus described my invention, what I claim as new and desire to secure by Letters Patent is:

1. A spring compressor comprising a frame; a spring engaging part on said frame; a bearing on said frame; a plunger reciprocatively mounted in said bearing in alignment with said spring engaging part, means connected to the plunger for reciprocating said plunger, and for locking said plunger when moved toward said engaging part.

2. A spring compressor comprising a frame, a spring engaging part on said frame, a bearing on said frame, a plunger reciprocatively mounted in said bearing in alignment with said spring engaging part, a lever pivotally mounted on said frame and a link connecting said lever and said plunger.

3. A spring compressor comprising a frame, a spring engaging part on said frame, a bearing on said frame, a plunger reciprocatively mounted in said bearing in alignment with said engaging part, a lever pivotally mounted on said frame and a link connecting said plunger and said lever, the connecting point of said lever and link being adapted to rest in such position, when the plunger is moved toward said engaging part by said lever and link, as to lock said plunger in said position.

4. A spring compressor comprising a frame, a spring engaging part on said frame, a bearing on said frame, a plunger reciprocatively mounted in said bearing in alignment with said engaging part, a lever pivotally mounted on said frame at one side of the axis of said plunger, and a link connecting said plunger and said lever, the connecting point of said lever and said link being such as to swing to the side of the pivot of said lever, when the plunger is moved toward said engaging part by said lever, whereby the plunger is locked in such position.

5. A spring compressor comprising a frame, a spring engaging fork on said frame, a plunger reciprocatively mounted in said frame in alignment with said fork, a

presser foot adjustably mounted on said frame adjacent said fork and means for reciprocating said plunger.

6. A spring compressor comprising a frame, a spring-engaging part on said frame, a plunger reciprocatively mounted on said frame in alinement with said engaging part, a lever pivotally mounted on said frame, a link pivoted at one end to said lever, said plunger being provided with a plurality of holes and a pin adapted to be inserted in any of said holes and to connect the lower end of said link to said plunger.

7. A spring compressor comprising a frame, a spring engaging part on said frame, a bearing on said frame, a plunger reciprocatively mounted in said bearing in alinement with said engaging part, a lever pivotally mounted on said frame, a link 20 pivotally connected at its upper end to said lever, said plunger being provided with a plurality of holes, said bearing being provided with a longitudinal slot with which said holes in the plunger are adapted to register, and a pin adapted to be inserted through said slot into any of said holes in the plunger and to connect the lower end of said link with said plunger

8. A spring compressor comprising a U-shaped frame, an engaging part on one arm

of said frame, a bearing on the other arm of said frame, a plunger reciprocatively mounted in said bearing in alinement with said engaging part, and means for reciprocating said plunger.

9. A spring compressor comprising a U-shaped frame, an engaging part on one arm of said frame, a plunger reciprocatively mounted on the other arm of said frame, a lever pivotally mounted upon said frame, the pivot of said lever being at the side of the axis of said plunger nearer the intermediate member of said U-shaped frame, and a link connected at one end to said plunger and at its other end to said lever, the connecting point of said link and lever being adapted to cross the axis of said plunger when the plunger is forced down by said lever and link and to rest at the side of the plunger axis opposite the side at which the lever pivot is located, whereby the plunger is locked in its lower position.

In testimony whereof, I have hereunto set my hand at San Francisco, California, this 20th day of November 1916.

HARRY I. MACKEEVER.

In presence of—

JOHN R. OBER,
P. S. PIDWELL.
